US00D810192S

(12) **United States Design Patent** (10) **Patent No.:** **US D810,192 S**
(45) **Date of Patent:** **** Feb. 13, 2018**

(54) **COPIER**

(71) Applicant: **SHARP KABUSHIKI KAISHA**,
Osaka-shi, Osaka (JP)

(72) Inventor: **Osamu Kawata**, Osaka (JP)

(73) Assignee: **Sharp Kabushiki Kaisha**, Osaka (JP)

(**) Term: **15 Years**

(21) Appl. No.: **29/547,698**

(22) Filed: **Dec. 7, 2015**

(30) **Foreign Application Priority Data**

Jun. 8, 2015 (JP) 2015-012607

(51) **LOC (11) Cl.** **16-03**

(52) **U.S. Cl.**

USPC **D18/39**

(57) **CLAIM**

The ornamental design for a copier, as shown and described.

DESCRIPTION

FIG. 1 is a top, front, right perspective view of a copier showing the new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The lines shown on the front of the copier illustrate a surface appearance.

The broken lines shown in the drawings illustrate portions of the copier that form no part of the claimed design.

1 Claim, 7 Drawing Sheets
